Primary Examiner — Darlington Ly(74) *Attorney, Agent, or Firm* — Dragon Sun Law Firm, PC; Jinggao Li; Nathaniel Perkins(57) **CLAIM**

The ornamental design for a pair of pedals for cycles, as shown and described.

DESCRIPTION

FIG. 1 is a perspective view of a pair of pedals for cycles embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof; and,

FIG. 7 is an enlarged bottom plan view thereof.

The broken lines shown in the figures depict portions of the pedals for cycles that form no part of the claimed design.
